Wilton D. Whipple of Douglas, Massachusetts

Letters Patent.

The schedule referred to in these Letters Patent and making part of the same containing a description in the words of the said Wilton D. Whipple himself of his improvement in the method of making or forming the eye of eyes, by drilling the same, — To all people to whom these presents shall come:

Be it known that I, Wilton Deller Whipple, of Douglas, of the County of Worcester, in the Commonwealth of Massachusetts, Mechanic, have invented a new and useful improvement in the method of making or forming the eye of eyes by drilling out the same, and that the following is a full and exact description of the construction and operation of the said machine as invented as improved by me.

The machine may be made of iron, wood, or of any material suitably strong and firm, the frame of the machine is of the form of a parallelogram, being composed of four pieces of wood or iron firmly joined together.

The part of the frame that unites the top of it is not directly over the corresponding part at the bottom, but for the sake of convenience, is placed a little back of it. At a convenient distance from the bottom of the frame, is a slot firmly turned into the body of the frame and side that which unites and connects the side of the frame at the bottom. Through the bottom of the frame and through this slot are two holes in each the hole in the slot being directly over those in the bottom of the frame.

At the top of the frame and in the right hand corner an open stand supporting the machine is a rod with the lower end of it resting upon a block attached to the side of the frame at a convenient distance from the top, the upper end of the rod is confined in like manner to another stand, attached to the top of the frame and at a convenient distance from the side, so that the rod has the position of a brace, making an angle with the side and top of the frame.

At the top of this rod, the rod is confined and held firmly while the eye is drilled and through the holes in the slot and bottom of the frame are two sets of iron, these are called steps, and are similar to each other and are placed upright. Both are moveable up and down. Between the slot and bottom is a bar of iron parallel

with them, with a hole in each and corresponding precisely with the hole in the block and bottom through which the stops are passed or inserted.

This bar is moveable up and down on the block and confined at either end by means of screws answering as keys. Through the centre of this bar, and between the stops, is a stationary screw, that is, a screw having only a rotating motion without moving forward or back. There is a thread in the central hole through the bar or screw to receive the stationary screw, so that by turning the stationary screw, the bar which is passed through it will be depressed according to the motion given to the stationary screw, and this screw is kept in its place or kept from rising when turned, by means of the slot.

On the top of the right hand stop, near the foot of the stock which holds the drill, there the foot of the stock and upward is cut an end-slip screw, the threads of which play into or receive the teeth of a pinion and which will be hereafter mentioned. Above this end-slip screw and firmly attached to the stock is a wheel, or drum, for the band connecting the machine with the moving power.

Above the drum is a wide slot in the block for the convenience of putting in and taking out the Drill. From the top of the stock to the top of the slot is a hole for the drill. This hole is not parallel with the side of the stock or perpendicular, but passes through obliquely, so that when the stock revolves, the point of the drill instead of turning on a point, describes with its point a small circle. This drill is firmly held in the stock by means of a screw, and when the stock is put into the block, it is inserted with its most prominent cutting point directly against that part of the stock where the screw enters; and the screw is inserted exactly on the largest side of the stock.

Above the slot and on the back side of the machine and resting on borg, arms attached to both sides of the frame is a shaft, upon the right hand end of which is a pinion, the teeth of which are received upon the teeth of the end-slip screw on the foot of the stock before mentioned. Upon the opposite end of this shaft is another end-slip screw, moving another pinion which is attached to the lower end of an upright shaft on the other side of the frame. This upright shaft is of equal length with the stock; from the upper end of this shaft, it is bent or crooked, that when it revolves, it drives the motion wheel by a crank.

The lower end of the crank part of the shaft revolves in revolving, a larger circle than the upper part. The diameter of the large circle thus described is equal

17400X

4441

To the greater width of the eye in the direction from the edge to the head or back of the eye and the diameter of the smaller circle, so that made by the upper end of the crank, is equal to the width of the eye, in the direction from the center of the edge of the eye to the centre of the back or head of the eye. To that part of the shaft which comprises the crank, is attached a sweep, placed horizontally, the other end of which on the right hand of the machine is attached to the upper end of the stock above the slot - upon this last end of the sweep is a slot through which passes the rod before named, so that this sweep moves the drill [the drill being in the stock] over all parts of the surface of the eye of the eye. —

Upon the left hand step and resting upon the upper end of it, is an upright sweep, and is called the second sweep; upon the upper end of which rests the end of the first sweep next to the crank. — The purpose of the second sweep is to sustain or support the end of the first sweep. Upon the top or upper end of the stationary screw, is a ratch wheel, and directly beneath this wheel and movable on the neck of the stationary screw, is an arm, and upon that part of the arm which is on the first side of the stationary screw is a foot nut which is fitted a dog for the ratch. —

To this part of the arm is attached one end of a spiral spring, and the other end is attached to the side of the frame. — Below the pinion on the part of the upright shaft, is an arm passing through the shaft opposite to the end of the arm on the neck of the stationary screw. — Explanation of the Drawing

Fig. I. E. upright shaft. a. e. crank on the shaft. b. pinion. d. passing through the foot of the shaft. b. second sweep. f. stock holding the drill. m. slot in the stock for the convenience of changing the drill. n. or. drill passing obliquely through the stock. i. screw to hold the drill firmly in the stock. q. apparatus to hold the eye during the process of drilling. m. Drill k. arm on the neck of the stationary screw. l. place of the dog for the ratch wheel showing where the spiral spring is attached to it. x. screw that holds the drill. —

Explanation of the Drawing -

Fig. I. A.B.C.D. Frame of the machine. e. shaft f. f. steps the right hand one supporting the drill and stock, and the left hand one supporting the sweep. g. g. g. bar of iron through which the step passes. b. stationary screw. i. i. screws answering as keys to confine the steps f. f. in the bar g. g. g. f. stock holding the drill. k. drum or wheel for the hand

connecting the machine with the moving power. *T.* screw or spiral thread round *z* with the pinion, *s.* *M.* slot in the stock for the convenience of changing the drill. *n. n.* drill, *o. o.* Rod passing through the slot in the first sweep.

p. Arm confined for the process of drilling. *q.* apparatus for firmly holding the arm, *r.* pinion on the shaft *S.* *u.* spiral thread, or endless screw on the shaft *S.* *v.* pinion on the upright shaft *W.* *w.* arm on the shaft *W.* *W.* upright shaft. *x* crank part of the shaft *W.* *a.* feet or horizontal sweep *b.* slot in the first sweep for the rod. *b.* second sweep, *c.* catch wheel on the stationary screw, *d.* arm moveable on the neck of the stationary screw, *m. m.* spiral spring to bring back the arm *d.* when moved by the arm *V.*

The drawing *Fig. I* represent the machine as it is when the drill is at that part of the edge nearest the edge. The band connecting the machine with the waterpower passing over the drum or wheel represented by *b.* when the machine is put in motion, the stock *j.* holding the drill *n. n.* is made to revolve, and as the endless screw *t.* is a part of the stock *j.* it revolves with it.

The endless screw plays into the leaves of the pinion *r.* attached to the horizontal shaft *S.* and the shaft *S.* is made to revolve, and as the endless screw *u.* is attached to the shaft *S.* this endless screw also revolves. The endless screw *u.* plays into the leaves of the pinion *z.* and turns the upright shaft *W.* and as the shaft *W.* turns the arm *V.* near the foot of it one end of the arm *V.* is brought in contact with the band (*b.* *Fig. 2*) in the arm *d.* and this makes the arm *d.* back. As the arm *d.* is back, the catch wheel *c.* which is attached to the stationary screw, *b.* is carried forward, the dog attached to the feet resting on the arm *d.* as represented in *Fig. 2*, catches into the catch when so carried forward, and there holds it. And as the arm *d.* is moveable round the neck of the stationary screw *b.* and when the arm *V.* has crowded the arm *d.* back, the arm *d.* [the arm *V.* having passed by] is suddenly restored to its former position by means of the spiral spring *m. m.*

When the arm *d.* was crowded back by the arm *V.* by the revolving of the upright shaft *W.* the catch wheel *c.* by means of the dog [*Fig. 2*] this dog moves with the arm *d.* being a part of it] was moved forward and as the catch wheel is firmly attached to the lip of the stationary screw, this stationary screw is made

to perform a part of a revolution, and as there is a thread or screw cut in the bar q.q.q. at the middle p. and as this stationary screw rests with its end upon the bottom of the frame, and as the slips f.f. are moveable up and down through the slot c. and bottom of the frame, the bar q.q.q. therefore the slips f.f. because confined to the bar by means of the screws i.i. were all raised upwards. And as the stock j rests upon the top of the right hand slip f. the stock j was raised upward at the same time, and consequently the drill n.n. and the second sweep b. which rests upon the top of the left hand slip f. was raised upward in the same manner, and this constituted the feed or the motion of the drill into the eye of the axe.

I will now describe the manner by which the drill is made to traverse and cut out all parts of the eye equally. The eye of the axe is made tapering or conical both ways to the centre. This is its usual shape and is so formed for the convenience of holding or wedging in the hilt or handle. My machine is so constructed as to give this form to the eye,

The lower end of the crank x. on the shaft w. describes when it revolves a large circle than the top or upper end of it, during the process of drilling out the eye of an axe, the first sweep a. which is placed horizontally slips or is raised upwards on the crank x. by means of stationary screw h. a distance equal to half the width of the axe.

I now suppose the machine to be in the same position as when the first operation of it began, because the motion now to be described was performed at the same time with that, as the shaft g. revolves, the upright shaft w. begins to revolve in like manner, and the first sweep a. being attached to the crank x. on the shaft w. as the shaft w. turns the stock j. & consequently the drill n.n. is carried from that part of the eye next to the edge of the axe, towards the head or back of the axe - and the drill traverses the whole width of the eye in half of a revolution of the shaft w. And at each successive semi-revolution of the shaft w. the first sweep a. by means of the stationary screw h. being raised upwards, a smaller circle is described by that particular part of the crank x. occupied by the first sweep a. and consequently a smaller circle is passed over by the drill, and in this way as the first sweep a. rises on the crank x. the eye of the axe is diminished in thickness or made tapering.

1400X

With the eye of the first sweep α next to the drill or σ , it is kept in its place by the rod 0.0 in the slot β , and in consequence of the sweep α turning on the rod 0.0 , and the sweep α being raised by each revolution of the shaft Ω and the inclined or oblique position of the rod 0.0 , the length of the sweep α is constantly diminishing, and with it the space or surface passed over by the rod 0.0 . And these two motions together produced by the shape of the crank χ , and the inclined position of the rod 0.0 , from the eye of the axe tapering both in breadth and thickness.

By making the crank χ regular and placing the rod 0.0 perpendicular, the axe would be of uniform breadth and thickness. When the machine has carried the drill one half way through the eye of the axe, the dog on the ratch wheel is raised, and by means of a weight attached to a rope or chain which is wound round the ratch wheel, the stationary screw is turned in opposite direction to that produced by means of the motion given it by the machine, and the stops δ , the bars g, g, j , the two sweeps α & β , the stock δ and the drill or σ are let down to their original position. The axe is then taken out and turned over, and the dog replaced upon the ratch wheel, and the process of drilling again commenced as before, and the other half completed in the same way.

All I claim in this specification as my invention or improvement is the application of machinery in causing forward the drill to the drilling out the eyes of axes in proper shape.

In witness whereof I have hereunto set my hand this twenty eighth day of November, one thousand eight hundred and thirty two.
